UNITED STATES PATENT OFFICE.

DALE M. BOOTHMAN, OF OAKMONT, PENNSYLVANIA, ASSIGNOR TO ALUMINUM SEAL COMPANY, OF PITTSBURGH, PENNSYLVANIA, A CORPORATION OF PENNSYLVANIA.

METHOD OF ATTACHING CAPS TO CONTAINERS AND OF FORMING HERMETIC SEALS.

Application filed October 9, 1924. Serial No. 742,555.

In my co-pending patent application, Serial No. 593,791, there is disclosed a closure seal for containers which comprises a metal cap having a depending skirt or flange which forms with the outer wall of the mouth of a container an annular space in which there is arranged, first a sealing gasket, and below the gasket an annular member which acts between the container 5 wall and cap flange to retain the cap upon the container, and in my co-pending patent application Serial No. 695,598 there is disclosed a machine for forming closure seals of the character shown in my first mentioned application. In both applications there is a disclosure of a method of forming the various closure seals shown in the first application.

The present invention relates to, and is directed towards the formation of closure seals by the method disclosed in said applications. However, the method for which protection is sought in this application is applicable to forming seals different than those disclosed in the first application, and is also applicable to the attaching of closure caps to containers where no hermetic seal is effected between the caps and containers. Furthermore, the method herein disclosed 25 may be practiced by the use of hand tools, as well as by machines other than that illustrated in the second application.

An object of this invention is to provide an improved method of firmly attaching a cap having a resilient metal flange to a container having a rigid open mouth.

A further object is to provide an improved method of not only firmly attaching a cap having a resilient metal flange to a container having a rigid open mouth, but also of simultaneously forming a hermetic seal between the cap and container.

According to this invention a closure cap having a resilient metal flange is attached to a container having a rigid open mouth by first applying the cap to the mouth of the container in such manner that the cap flange surrounds the outer wall of the container adjacent to its mouth, and then, while the cap flange is free to expand outwardly, wedging an annular retaining member between the container wall and cap flange in such a manner that the resilient cap flange is pressed outwardly and placed under initial tension, by virtue of which tension the

flange subsequently presses inwardly upon the retaining member to hold the cap upon the container.

The container may be, and preferably is, a glass jar, bottle, or the like, which is inherently rigid, but may also be a metal can, pail, or the like, having a rigid open mouth. As to the retaining member, it may be a sealing gasket in the form of a continuous ring or in the form of a string or strip. 65 However, it is preferably a wire.

The container and cap flange are so formed that when the cap is applied to the container an annular wedge-shaped space is formed between the cap flange and the outer 70 wall of the container with its wider end adjacent to the outer edge of the flange. By forming such a wedge-shaped annular space between the container and flange, and by so holding the cap upon the container that the 75 flange is free to expand outwardly, the retaining strip may be easily entered into the space and be readily wedged into position to place the flange under initial outward tension. The wedge-shaped annular space 80 may be formed between a container having an outwardly tapering outer wall and the flange of the cap extending at right angles to the top of the cap, or it may be formed between a container having a truly cylindrical outer wall adjacent to its mouth and a cap flange which flares outwardly from 85 the top of the cap.

To more securely hold the cap upon the container, the lower edge of the cap flange 90 may be crimped inwardly below the retaining member after the latter has been wedged into the annular space between the container and flange.

The invention may be further explained 95 and fully understood by describing it in greater detail with reference to the accompanying drawings which illustrate various types of seals which may be formed in the practice of the invention, and which also 100 diagrammatically illustrate mechanism whereby the invention may be practiced. Fig. 1 of the drawings shows a cap applied to a container before being attached to it by an annular retaining member; Fig. 2 the 105 container of Fig. 1 with a retaining member wedged between its outer wall and the cap flange; Fig. 3 a finished seal of the type illustrated in Fig. 2 with the lower edge of the cap crimped inwardly; Figs. 4, 5, 6 and 110

7 various types of seals which may be formed in the practice of the invention; Fig. 8 a seal formed at the mouth of the metal container; Fig. 9 a seal formed at the 5 mouth of a bottle having a truly cylindrical outer wall; Figs. 10, 11 and 12 diagrammatic representations of apparatus which may be used in the preferred practice of the invention; and Fig. 13 an elevation of a 10 container with a finished seal attached to it.

Having reference first to Figs. 1, 2 and 3, a cap 1, which is preferably formed entirely of metal, but which may be variously constructed providing it has a resilient metal 15 flange 2, is shown in Fig. 1 as being applied to the open mouth of glass container 3 prior to the wedging in of a cap-retaining member. In this instance the outer wall of the container tapers outwardly so that an annular wedge-shaped chamber 4 is formed between it and the flange 2 which is perpendicular to the top of the cap. The cap-retaining member illustrated in Fig. 2 is a ring 5 made of any suitable gasket-forming 20 material such as rubber. With the cap applied to the container and suitably held firmly on it without confining the flange, the retaining ring may be wedged between the container and flange by a suitable roller or other 25 tool 6. The pressure exerted upwardly upon the retaining member is sufficient to cause the cap flange to slightly bulge outwardly, as is illustrated in a somewhat exaggerated manner in Fig. 2. Such outward pressure upon 30 the flange places it under initial tension so that the flange subsequently continually presses inwardly upon the retaining member. As is indicated at 7 in Fig. 3, after the retaining member has been wedged into position 35 the lower edge of the cap may be crimped inwardly to prevent outward movement of the retaining member, and hence to more securely attach the cap to the container. By so attaching the cap to a container, the 40 cap is not only firmly secured in position, but the retaining member serves also to form a hermetic seal between the container and cap.

If desired, a cap may be similarly attached to and sealed upon a container by a gasket in 45 the form of a continuous strip. To make such an attachment and seal, preferably two turns of a combined cap-retaining and sealing strip 8 (Fig. 4) are wedged between a cap flange 2^a and the outer wall of a container 3^a. The upper most turn of the gasket serves primarily as a sealing member and the lower turn as a cap-retaining member. Preferably the outer end of the strip is arranged to project below the lower edge of the flange, as indicated at 9, so that it may be readily engaged to remove it from between the container and flange. This may be done by merely pulling downwardly upon the end 9 of the strip.

While the cap-retaining member may be a

gasket in the form of a ring or a string as has been explained, it preferably consists of a wire wedged between the container and cap flange in the manner described. The wire may be of any suitable metal, but is preferably aluminum. In Fig. 5 there is illustrated a container 3^b having a cap 1^b attached to it by slightly more than a single turn of a wire 10 wedged between the container and cap flange. In this case the outer end 9^b of the wire may also project below the lower edge of the flange for engagement to remove it. If desired, a hermetic seal may be formed between the top of the container and the top of the cap by interposing between them an annular gasket 11. 75

In the seal illustrated in Fig. 6 a cap 1^c is retained upon a container 3^c by means of a wire 10^c, and a hermetic seal is formed between the cap and container by a gasket ring 5^c similar to that illustrated in and explained with reference to Figs. 2 and 3. In forming this seal, the gasket ring 5^c is first wedged between the container and cap flange and thereafter the cap retaining wire 10^c is 90 wedged into the position indicated. 85

The preferred form of seal made according to this invention is that illustrated in Fig. 7 in which a hermetic seal is formed between a container 3^d and a cap 1^d by a string-like gasket 8^d, and in which the cap is attached to the container by a strip of wire 10^d. As indicated, the outer end 12 of the sealing gasket 8^d is preferably arranged below the inner end 13 of the wire 10^d, so that when the wire is removed by engaging and pulling downwardly upon its outer exposed end 9^d, the inner end 13 of the wire will cause the outer end 12 of the gasket to be exposed below the cap flange so that it in turn may thereafter be engaged and removed. The manner of forming this particular seal will presently be explained with reference to mechanism diagrammatically illustrated in Figs. 10, 11 and 12. 100 105 110

It has been previously explained that it is desirable to so shape the cap and the outer wall of the container that there is an annular wedge-shaped space between the flange and container when the cap is applied to it. In the forms of seals thus far explained such an annular space is effected by providing a container having an outwardly tapering outer wall and a cap having a flange which is perpendicular, or substantially so, to its top. In the structure shown in Fig. 9, a wedge-shaped annular space 15 is formed between a truly cylindrical outer wall of the top of a bottle 16 and a flange 2^e which flares outwardly from the top of a cap. The cap in this instance is attached to the container by a retaining wire 10^e, but may be attached by any of the other forms of retaining members contemplated herein. To properly center the cap on a container 120 125 130

- when the two are assembled prior to the wedging of the cap-retaining member, the cap may, as illustrated in Fig. 9, be so formed as to turn downwardly immediately adjacent to the outer edge of the top of the container mouth as indicated at 26. Fig. 9 further illustrates the attachment of a cap to a container by means of a cap-retaining wire without simultaneously forming a hermetic seal between the cap and container. If desired the container may be sealed otherwise than during the cap-attaching operation, as for example by means of a suitable cork 17.
- 15 In the various forms of seals thus far illustrated the rigidity of the mouths of the containers is inherent in the material of which they are formed. However, the invention is applicable to attaching closure caps to containers which of themselves are not inherently rigid, providing the mouths of the containers are suitably rendered rigid so that, when the cap-retaining member is wedged between them and the flanges of the cap applied to them, the flanges will be placed under initial outward tension. In Fig. 8 there is illustrated a container 3^d formed of sheet metal, the mouth of which is made rigid by so shaping it as to form an annular bead 18. A cap 1^d may be attached to such a container by means of a gasket ring 5^d or by any of the forms of seals illustrated in the other figures, and which have previously been explained.
- 30 35 In Figs. 10, 11 and 12 there is somewhat diagrammatically illustrated mechanism for attaching a cap to a container which may be used to form according to this invention the various seals which are herein illustrated and which have been described, but which is particularly suitable for forming the seal illustrated in Fig. 7. These views show successive steps in the cap-attaching and sealing operation. The mechanism 40 45 which is the same as that illustrated in my said application Serial No. 695,598, includes a rotatable support 18 for the container 3^d and a rotatable head 19 for holding a cap 1^d applied to the mouth of the container. Projecting upwardly between the cap flange and the outer wall of the container there is a roller 20 (Fig. 10) for wedging between the flange and container the string-like gasket 8^d which is adapted to be fed to the 50 55 roller through a tube 21. After the holder 18 and head 19 have made slightly more than a complete revolution, the inner end of the retaining wire 10^d is fed through a tube 22 (Fig. 11) and upon a second roller 23 which wedges the wire against the gasket, which in turn is further wedged into sealing position. After the support 18 and head 19 have made somewhat more than a second complete revolution, they are simultaneously moved upwardly with relation to the 60 65 wedging rollers 20 and 23, as indicated in Fig. 12, so that the outer end 9^d of the retaining wire may extend below the lower edge of the cap flange. Thereafter, a crimping roller 24 presses the lower edge of the flange inwardly, as is also illustrated in Fig. 12. The completed seal is illustrated in Fig. 13.
- 70 75 The customary manner of forming a side seal between a cap and a container is to place a gasket within the flange of the cap and subsequently spin the flange inwardly which places it under an initial compression with the result that the tendency of the flange of a completed seal is to spread outwardly.
- 80 85 90 The characterizing feature of the improved method of attaching a cap to a container is that the resilient flange of the cap is pressed outwardly by wedging between it and a container having a rigid open mouth a cap retaining member which places the flange under initial tension. By virtue of such tension the flange continuously presses inwardly upon the retaining member to hold the cap upon the container. In addition to this, the method contemplates in its more specific aspects the simultaneous forming of a hermetic seal between the cap and container, the seal preferably being effected by wedging a strip of gasket between the container and cap flange, and the attachment of the cap to the container by thereafter wedging a wire between the cap and container back of the sealing strip.
- 95 100 105 110 According to the provisions of the patent statute, I have described the principle and manner of practicing the invention with reference to various forms of seals. However, I desire to have it understood that, within the scope of the appended claims, the invention may be practiced otherwise than specifically illustrated and described, and in the formation of other seals than those illustrated.
- I claim as my invention:
1. The method of attaching a cap to a container having a rigid open mouth, which comprises first applying to the mouth of the container a cap having a resilient metal flange surrounding the outer wall of the container adjacent to its mouth, said flange being free to expand outwardly, and then pressing the flange outwardly by wedging a cap retaining member between the cap flange and the outer wall of the container, thereby placing the flange under initial tension by virtue of which it subsequently presses inwardly upon the retaining member.
  2. The method of attaching a cap to a container having a rigid open mouth, which comprises first applying to the mouth of the container a cap having a resilient metal flange surrounding the outer wall of the container adjacent to its mouth, said flange

being free to expand outwardly, and then 5
pressing the flange outwardly by wedging
a cap retaining wire between the cap flange
and the outer wall of the container, there-
5 by placing the flange under tension by virtue
of which it subsequently presses inwardly
upon the wire to hold the cap firmly at-
tached to the container.

3. The method of attaching a cap to a
10 container having a rigid open mouth, which
comprises first applying to the mouth of the
container a cap having a resilient metal flange
surrounding the outer wall of the container
adjacent to its mouth, said flange being free
15 to expand outwardly, then pressing the
flange outwardly by wedging a cap retaining
member between the cap flange and the outer
wall of the container and above the outer
edge of the flange, thereby placing the
20 flange under initial tension, and finally
crimping inwardly the outer edge of the
flange below the cap retaining member.

4. The method of attaching a cap to a
25 container having a rigid open mouth, which
comprises applying to the mouth of the con-
tainer a cap having a resilient metal flange
surrounding the outer wall of the container
adjacent to its mouth and forming with such
30 wall a wedge-shaped annular space, said
flange being free to extend outwardly, and
then pressing the flange outwardly by wedg-
ing a cap retaining member in said space and
between the container and cap flange, thereby
35 placing the flange under initial tension
by virtue of which it subsequently presses
inwardly upon the cap retaining member.

5. The method of hermetically sealing a
40 container and attaching a cap to it, which
comprises applying to a container having a
rigid open mouth a cap having an uncon-
fined resilient metal flange surrounding the
outer wall of the container adjacent to its
45 mouth and forming with such wall a wedge-
shaped annular space, and wedging in said
space and between the container and cap
flange first a sealing strip of gasket material
and then a cap-retaining wire, whereby the
50 flange is placed under initial tension by
virtue of which it subsequently presses in-
wardly upon the gasket and wire to tighten
the seal and to hold the cap upon the con-
tainer.

the cap flange subsequently presses inwardly 50
upon the gasket.

6. The method of sealing a container and
attaching a cap to it, which comprises first
applying to a container having a rigid
mouth a cap having an unconfined resilient 55
metal flange surrounding the outer wall of
the container adjacent to its mouth, and then
wedging between the container and cap
flange first a sealing gasket and then back
of the gasket a cap-retaining strip, whereby 60
the flange is pressed outwardly and placed
under initial tension by virtue of which it
subsequently presses inwardly upon the
gasket and strip to tighten the seal and hold
the cap upon the container. 65

7. The method of sealing a container,
which comprises first applying to a container
having a rigid mouth a cap having an un-
confined resilient metal flange surrounding
the outer wall of the container adjacent to 70
its mouth, and then wedging between the
container and cap flange first a sealing
gasket and then back of the gasket a cap-
retaining strip of wire whereby the flange
is pressed outwardly and placed under 75
initial tension by virtue of which it sub-
sequently presses inwardly upon the gasket
and wire to tighten the seal and hold the
cap upon the container.

8. The method of hermetically sealing a 80
container and attaching a cap to it, which
comprises applying to a container having a
rigid open mouth a cap having an uncon-
fined resilient metal flange surrounding the
outer wall of the container adjacent to its 85
mouth and forming with such wall a wedge-
shaped annular space, and wedging in said
space and between the container and cap
flange first a sealing strip of gasket material
and then a cap-retaining wire, whereby the 90
flange is placed under initial tension by
virtue of which it subsequently presses in-
wardly upon the gasket and wire to tighten
the seal and to hold the cap upon the con-
tainer. 95

In testimony whereof, I sign my name.

DALE M. BOOTHMAN.
